UNITED STATES PATENT OFFICE.

HARRY KAUFMAN AND FRANK M. KAUFMAN, OF PHILADELPHIA, PENNSYLVANIA.

WOVEN PILE FABRIC.

1,169,835.

Specification of Letters Patent.

Patented Feb. 1, 1916.

Application filed December 11, 1914. Serial No. 876,615.

To all whom it may concern:

Be it known that we, HARRY KAUFMAN and FRANK M. KAUFMAN, citizens of the United States, residing at Philadelphia, county of Philadelphia, and State of Pennsylvania, have invented certain new and useful Improvements in Woven Pile Fabrics, of which the following is a specification.

Our invention relates to improvements in woven pile fabrics, the object of the invention being to provide a cut pile fabric in which the warp pile threads forming the tufts are securely woven into the fabric backing and project uniformly from the fabric, presenting a smooth unbroken surface.

A further object is to provide a woven pile fabric in which the alternate warp pile threads in any series extend in the same direction from one backing fabric to the other, and adjacent pile threads extend in opposite directions from one backing fabric to the other, all pile threads being uniformly woven into the upper and lower backing fabrics.

With these and other objects in view, the invention consists in certain novel arrangement of threads in the weaving of the fabric as will be more fully hereinafter described and pointed out in the claim.

In the accompanying drawings: Figure 1 is an exaggerated view in longitudinal section illustrating our improved pile fabric. Figs. 2, 3, and 4 are views similar to Fig. 1, but each view showing but one pile thread of the series connecting the backing fabrics, and Fig. 5 is a diagrammatic plan view of the fabric after the pile is cut.

Our improved pile fabric consists of top and bottom backing fabrics X and Y respectively, connected by warp pile threads arranged in series of three threads to a series, said pile threads given reference numerals 1, 2, and 3, respectively.

The top backing fabric X consists of binding warp threads 6 and 7, and weft threads A, B, C, D, E, and F, woven between the binding warp threads 6 and 7. The lower backing fabric Y consists of binding warp threads 4 and 5 with weft threads A', B', C', D', E', and F' woven therein.

The upper and lower picks of the weft threads are simultaneously woven by the shuttle, and hence for convenience of description, these pairs of picks of the weft threads are given corresponding letters, the

reference letters of the picks of the bottom fabric being primed as above described.

In Fig. 1, the series of three pile threads 1, 2, and 3, are illustrated showing how the several threads are woven into the backing fabrics X and Y, and by arrows indicating the direction of the weave of said pile threads.

In Figs. 2, 3, and 4, the backing fabrics are illustrated, and in connection therewith one of the threads 1, 2, and 3, respectively is illustrated to show clearly the manner of weaving the same. Referring to these Figs. 2, 3, and 4, it will be noted first, that pile thread 1 is positioned over weft thread A, thence under weft thread B, thence over weft thread C, thence extends from the top fabric X to the bottom fabric Y, and passes under weft thread D', thence over weft thread E', thence under weft thread F', and to the point of starting another series over weft thread A. Pile thread 2 passes over weft thread A in the top fabric X, thence extends to the bottom fabric Y and under weft thread B', thence over weft thread C', thence under weft thread D', thence back to the top fabric X, over weft thread E, and thence under weft thread F to the point of starting another series over weft thread A. Pile thread 3 extends over weft thread A', thence under weft thread B', thence to the top fabric X over weft thread C, thence under weft thread D, thence over weft thread E, thence back to the bottom fabric Y, and under weft thread F' to the point of starting another series over weft thread A'.

By reference particularly to Fig. 1, it will be noted that each alternate pile thread extends in the same direction from one fabric to the other, and that each adjacent pile thread extends in opposite directions from one backing fabric to the other. The pile threads, therefore, maintain throughout the surface of the fabric a uniform disposition so that no two adjacent tufts have a tendency to separate or to cross, all projecting alike from the backing and insuring a pile fabric of uniformly smooth and unbroken surface free from ridges, grooves, or other marking to detract from the appearance of the fabric. Furthermore, it will be noted that each tuft of the pile is tightly woven into the backing fabric and cannot work out of the backing fabric in any ordinary wear.

Various slight changes might be made in

the general form and arrangement of parts described without departing from our invention and hence we do not limit ourselves to the precise details set forth, but consider ourselves at liberty to make such changes and alterations as fairly fall within the spirit and scope of the appended claim.

Having thus described our invention, what we claim as new and desire to secure 10 by Letters Patent is:

A pile fabric, comprising top and bottom backing fabrics, a series of three pile threads connecting the backing fabrics, the alternate pile threads extending in the same 15 direction from one backing fabric to the other, and the adjacent pile threads extending in opposite directions from one backing

fabric to the other, said backing fabrics consisting of weft threads and binding warp threads, a filling shot of each backing fabric located between each pair of pile threads, and the said shots located in parallelism one above the other, the said pile threads in both top and bottom fabrics woven with three of said shots, and between the binding warp 20 threads, substantially as described.

In testimony whereof we have signed our names to this specification in the presence of two subscribing witnesses.

HARRY KAUFMAN.
FRANK M. KAUFMAN.
